UNITED STATES PATENT OFFICE.

ALBERT B. SHIVELY, OF LAUREL, NEBRASKA.

HOG-WATERING TROUGH.

Application filed June 10, 1922. Serial No. 567,297.

To all whom it may concern:

Be it known that I, ALBERT B. SHIVELY, a citizen of the United States, residing at Laurel, in the county of Cedar and State of Nebraska, have invented certain new and useful Improvements in Hog-Watering Troughs, of which the following is a specification, reference being had therein to the accompanying drawings.

This invention relates to a hog (watering) trough, and the object of my invention is the construction of a simple and efficient device for feeding or watering animals, such as hogs, and which device can be installed in, preferably, the front of a pen, and can be rotated to cause the device to extend into the aisle or beyond the outside of the pen, to allow the device to be cleaned or filled, at the will of the operator.

Another object of the invention is the construction of a movable or rotatable feeding device, built into a pen, which will also form a gate way or run way for little pigs to be allowed to pass out of the pen, or driven into the pen, as the operator desires.

With these and other objects in view, my invention comprises certain novel combinations, constructions and arrangements of parts as will be hereinafter described, illustrated in the accompanying drawings, and more particularly pointed out in the appended claims.

In the drawings:

Figure 1 is a perspective view of a plurality of pens and an aisle or "hall way," equipped with my novel watering devices.

Figure 2 is a view, in front elevation, of a device constructed in accordance with the present invention, while

Figure 3 is a view, in elevation, showing the feeding receptacles turned at right angles to the position thereof shown in Fig. 2.

Figure 4 is a sectional view, taken on line 4-4, Fig. 2, and looking in the direction of the arrows.

Figure 5 is a sectional view, taken on line 5-5, Fig. 2, and looking in the direction of the arrows.

Figure 6 is a view, partly in section, of the operating handle.

Figure 7 is a perspective view of the top plate.

Figure 8 is a perspective view of the shaft.

Figure 9 is a perspective view of the sleeve.

Figure 10 is a sectional view similar to

Fig. 5, with one of the feeding receptacles removed from the block, and the block and receptacle at right angles to the frame, to allow the run way for little pigs to pass back and forth, from the pen to the aisle, at the will of the operator.

Referring to the drawings by numerals, 1 designates the pens, and 2 is the aisle.

I construct one of my devices on the front of each pen. I first form an opening 3 in the front of the pen, then I place a vertical shaft 4 in the front of the pen, which shaft 4 is journaled at its lower end in the sleeve 5. The upper end of the shaft extends beyond the top of the pen, and placed over the extended end of the shaft is top plate 6. This plate 6 is fastened to the top of the pen, and at its center is provided with an apertured, square stud 7, through which stud 7 the shaft 4 extends. The shaft 4 is square in cross section a greater part of its length, so that the square aperture 8, of the operating handle 9, will fit snugly upon the shaft, and will enable the operating handle to turn the shaft at the will of the operator. The operating handle is provided with a square, depending cap 10 that normally fits over the square stud 7, so that the shaft 4 is locked against accidental displacement by the hogs rooting against the receptacle 11. Inasmuch as the operating handle is slidably mounted upon the shaft 4, the operator can easily lift up on the handle to release the same from the squared stud 7 and then, by turning the handle, the shaft will be rotated for moving or rotating the feed and watering receptacles 11.

The shaft 4 is rounded, at 12, so that by moving the operating handle up until the aperture 8 registers with the round portion 12, the handle can be rotated upon the shaft without operating the same. A cotter pin 13 extends through aperture 14 (Fig. 8) of the shaft to prevent accidental displacement of the operating handle off said shaft.

It is to be noted that the operating handle 9 constitutes not only means for operating the shaft, but when it is "dropped" down against the top plate 6, the plate and handle constitutes means for locking the shaft 4 against rotation and consequently holding the receptacle 11 projecting into the pen 1.

Each of the receptacles 11 comprises a body 15 and the body is provided with an inclined wall 16, to allow the hogs to have

ready access to the food or water in the receptacle; the body 15 is provided at its sides with guards 17, that prevent of the rooting of the food out of the receptacle by the hogs, and also greatly minimizes the amount of food or liquid spilled over the side of the receptacle.

I preferably use two receptacles in connection with each pen, and these receptacles are fastened by bolts 18, extending through the block 19; block 19 is mounted upon the shaft 4, within opening 3, and rotates with the shaft 4; consequently, upon the shaft 4 being rotated, the block 19, carrying receptacles 11, will cause the receptacles to alternately be extended into the aisle.

In Fig. 10, I have shown my device with one of the receptacles 11 removed from the block 19, to provide a run way for little pigs to escape from the pen 1, or be driven into the pen as the operator desires; this can be accomplished by turning the block 19, by reason of rotating shaft 4, at right angles with the opening 3, allowing one half of the opening to be free to produce the run way for the animals to pass back and forth, if desired.

It is to be noted that the front of the pen constitutes a support, having opening 3 therein, in which opening the receptacle, or receptacles 11 are movably mounted.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

1. In a device of the class described, the combination with a support provided with an opening, of a rotatable shaft on said support and extending across said opening, a plate provided with an apertured stud on said shaft and support, an operating handle provided with a cap on said shaft and said cap adapted to fit over said apertured stud,

and a receptacle supported by said shaft within said opening.

2. In a device of the class described, the combination with a support provided with an opening, of a rotatable shaft extending through said support and across said opening, said shaft projecting above the top of the support, a top plate on said shaft and resting upon the top of the support, said top plate provided with a squared stud around said shaft, an operating handle slidably mounted on said shaft above said top plate, said operating handle provided with a depending, squared cap adapted to fit over the square stud, and a receptacle in said opening and carried by said shaft.

3. In a device of the class described, the combination with a support provided with an opening, a shaft carried by said support and extending across said opening, a plate provided with a stud around said shaft and resting upon said support, an operating handle slidably mounted upon the shaft above the plate, said handle provided with a depending cap fitting upon said stud of the plate, means on the cap and stud for preventing rotation of the shaft when said cap and stud are engaging, and a receptacle carried by the shaft within said opening.

4. In a device of the class described, the combination with a support, of a movable shaft carried by said support, a plate on said support and around said shaft, a bodily movable operating handle on said shaft contiguous to said plate, means for locking said handle upon said plate, and a receptacle carried by said shaft.

5. In a device of the class described, the combination with a support, provided with an opening, of a rotatable shaft extending through said opening, a block within the opening and secured to said shaft, receptacles on opposite sides of said block, and means extending through the block and the upper parts of said receptacles securing the receptacles to the block.

In testimony whereof I hereunto affix my signature.

ALBERT B. SHIVELY.
